L. D. SHAW.
Relief Valve.

No. 230,828.

Patented Aug. 3, 1880.

Inventor.

Loring D. Shaw

UNITED STATES PATENT OFFICE.

LORING D. SHAW, OF BOSTON, MASSACHUSETTS.

RELIEF-VALVE.

SPECIFICATION forming part of Letters Patent No. 230,828, dated August 3, 1880.

Application filed October 4, 1879.

To all whom it may concern:

Be it known that I, LORING D. SHAW, of Boston, county of Suffolk, and State of Massachusetts, have invented certain new and useful Improvements in Automatic Relief-Valves; and I do hereby declare that the following is a full, clear, and exact description thereof, which will enable others skilled in the art to which it pertains to make and use the same, reference being had to the accompanying drawings, and to the letters thereon, which form a part of this specification.

My invention relates to improvements in automatic relief apparatus, and is to be attached to steam fire-engines and steam fire-pumps, and is for the purpose of preventing the bursting of fire-hose if the pressure be unduly increased therein, and is used in connection with stop-cock or cut-off nozzle, so that the hose-men or pipemen can at any time instantly shut off the flow of water at the pipe without injury to the engine or bursting the hose, by which means it gives them absolute control of the amount of water thrown into the building.

This my invention is also useful for the "Holly" system of water-works for fire purposes.

It consists in the combination of a cylinder of two different diameters, with its induction and delivery passages, and provided with movable pistons connected together and adjustable by a hand-screw, with a double-acting piston-valve.

It finally consists in the particular construction and arrangement of the independent movable pistons and valve, situated one within the other, and moved automatically by the action of the increased or diminished pressure of the water on the hose.

In the drawings, Figure 1 represents longitudinal section. Fig. 2 represents longitudinal section of movable pistons and valve enlarged, in order to more fully explain my invention.

In the accompanying drawings similar letters indicate similar parts.

a, a' represents a cylinder of two different diameters, as shown in Fig. 1, with induction-passage b , and delivery-passage c , provided with pistons, d, d' , connected together by the

hollow piston-rod e , and movable within the cylinder a, a' . The induction-passage b is connected with the delivery side of the pump, and the delivery-passage c is connected with the induction or suction side.

When pistons d, d' fall to their lowest position, piston d' passes below and opens the delivery-passage, by which means it offers a free delivery of the water from the delivery side of the pump, through induction-passage b , cylinder a , and delivery-passage c , to the suction or induction side of pump.

f is an independent hollow adjustable hand-screw to regulate the travel of pistons, so that any desired pressure can be maintained on the hose when the pumps are working and the stop-cock on the hose is closed.

Situated within piston d , Fig. 2, is pressure-chamber g , provided with its openings h , and passage through valve-seat k , and communicating with valve-chamber i . Valve-chamber i has its openings l communicating with the space around valve-chamber i and above piston d . Within the valve-chamber i is a double-acting piston-valve, m , movable in a vertical direction, and held to its seat by means of a spiral spring, n , adjustable so as to maintain any desired pressure. Up and into this piston-valve m extends a recess, from which a series of holes or ports, p , communicate with valve-chamber i . Extending into the above recess is that part of the hollow piston-rod that extends up and beyond piston d , and is for the purpose of preventing the flow of water through hollow piston-rod when the piston-valve is in its seat. When the piston-valve is in its seat communication is established between space above piston d , valve-chamber i , and ports p , through piston-valve m , hollow piston-rod e , and hollow hand-screw f , to the atmosphere.

Piston d being in area larger than piston d' , the pressure of the water coming in contact between them in cylinder a will cause the said pistons to remain in their highest position, and the piston d' will cut off communication through delivery-passage c .

The operation of this valve is as follows: When the pressure of the water in the hose is suddenly increased above what the piston-valve m is set to regulate, by closing the cut-

off nozzle the said piston-valve will be forced to its highest position, the communication will be cut off through ports *p* from above piston *d*, and the water will be forced through the 5 openings *h*, valve-seat *k*, pressure-chamber *g*, and openings *l* to space above piston *d*, around valve-chamber *i*, by which means the pressure of water will be equalized above and below piston *d*. The pressure on piston *d'* will 10 force pistons *d d'* to their lowest positions, opening delivery-passage *c* and offering free passage of the water from the delivery side to the induction side of the pump.

When the pressure is still more reduced, by 15 again opening the cut-off nozzle on the hose, and becomes less than the pressure to which piston-valve is set, the spiral spring *a* will force said valve to its seat, and the water above piston *d* will flow through openings *l*, 20 ports *p*, piston-valve *m*, hollow piston-rod *e*, and hollow hand-screw *f* to the atmosphere. Piston *d*, being larger than piston *d'*, will cause them to rise to their highest position.

From the above it will be seen that my relief apparatus is working perfectly automati- 25

cally in opening and closing by the action of the increased or diminished pressure of water on the hose.

What I wish to secure by Letters Patent and claim is—

1. In combination with a fire-engine pump, the cylinder *a a'*, having induction-passage *b* and delivery-passage *c*, pistons *d d'*, connected by the hollow piston-rod *e*, the said pistons being of different areas and movable within the cylinder *a a'*, the hollow adjusting-screw *f*, pressure-chamber *g*, with its openings *h*, and valve-chamber *i*, with its openings *l*, and valve-seat *k*, substantially as set forth. 35

2. In combination with a cylinder and its piston, the double-acting piston-valve *m*, situated within valve-chamber *i*, and provided with ports *p*, hollow piston-rod *e*, communicating with said ports, the spiral spring *n*, and its adjusting-screw *o*, substantially as described. 40 45

LORING D. SHAW.
